UNITED STATES PATENT OFFICE.

CHARLES DUCAS, OF NEW YORK, N. Y., ASSIGNOR TO JACOBS-SHUPERT UNITED STATES FIRE-BOX COMPANY, OF NEW YORK, N. Y., A CORPORATION OF PENNSYLVANIA.

FIRE-BOX.

1,181,650.

Specification of Letters Patent.

Patented May 2, 1916.

Application filed April 24, 1914. Serial No. 834,036.

To all whom it may concern:

Be it known that I, CHARLES DUCAS, of New York, in the county of New York, and in the State of New York, have invented a 5 certain new and useful Improvement in Fire-Boxes; and do hereby declare that the following is a full, clear, and exact description thereof.

My invention relates particularly to locomotive fire-boxes and especially locomotive fire-boxes adapted to utilize tubes for the transference of heat to the water around the fire-box.

The object of my invention is to provide 15 a fire-box equipped with water-tubes, which is so arranged that the expansion and contraction of the various parts will not loosen the tubes in their sockets. In order to carry out this portion of my invention the 20 tubes are preferably curved at least in part whereas the ends of the tubes are connected to portions of the fire-box which are rigidly supported in a pedestal-like manner at the front and rear of the fire-box by substantially vertical plates.

Another object of my invention is to provide 25 a fire-box, and especially a fire-box of the above type, which is so arranged that a man can readily enter the interior of the water space so as to inspect, clean or wash the interior, or to make repairs either to the tubes or other portions of the crown and roof sheets and the staying means attached thereto without the necessity of disconnecting any of the parts other than the man-hole covers provided for this purpose.

A further object of my invention is to provide 30 a fire-box with tubes so arranged that they effectively confine the flames and heated gases within the fire-box so as to secure a maximum of heating surface and of transference of the heat to the water.

A further object of my invention is to provide 35 an advantageous strengthening means for the portions of the sheets through which the ends of the tubes pass, so as to compensate for the removal of the material from the sheet to permit the entry of the ends of the tubes.

A still further object of my invention is to provide 40 an advantageous strengthening means for the back-head, which contains openings or doors to allow the entrance of workmen to the interior of the fire-box.

Another object of my invention is to arrange 45 the parts in such a manner that the

main portions of the tubes located at the bottom of the fire-box may be made vertical while the throat sheet at the forward end of the fire-box may be nevertheless located in an inclined position.

Still another object of my invention is to provide 50 a form of construction immune from disastrous explosion due to low water conditions, by making the roof and crown sheets of transverse sections and hence confining any rupture to the particular section so affected.

While my invention is capable of embodiment in many different forms, for the purposes of illustration I have shown only one form thereof in the accompanying drawings, in which,

Figure 1 is a perspective view partly in section of a portion of a fire-box made in 55 accordance with my invention; Fig. 2 is a longitudinal vertical section of the same; Fig. 3 is an end elevation partly in section of the same; Fig. 4 is a perspective view of one of the forward corners of the fire-box; Fig. 5 is a perspective view of one of the rear corners of the fire-box; and Fig. 6 is an enlarged detail of the plates through which the upper ends of the tubes pass, showing the strengthening means at this point.

In the drawings I have shown a roof sheet made up of a plurality of U-shaped sections 1, having outwardly directed flanges 2, which are riveted together. The foremost one of these U-shaped sections 1 is riveted in 60 a similar manner to a throat sheet 3, which in turn is riveted to a boiler sheet 3a. Between the flanges of the adjacent U-shaped sections 1 there are staying plates 4 having transverse openings 5 to permit the circulation of the water and steam and through which the back-head brace rods hereinafter referred to may pass. The lower edges of the plates 4 are located in a similar manner between upwardly directed flanges 6 on U-shaped sections 7 forming a crown sheet. The foremost U-shaped section 7 is riveted 65 to the top of a flue sheet 8 which is arranged to receive fire-tubes 9. The crown sheet is preferably arched to a slight degree in order to closely conform to the location of the fire-tubes 9, and the roof sheet is preferably arched so as to be parallel to the crown sheet. Between the throat sheet 3 and the flue sheet 8 there are a number of stays 10.

At the rear of the fire-box the U-shaped section 7 at that point is riveted to a door sheet 110

11 and the U-shaped section 1, which is located at the rear end of the roof sheet is riveted to a back-head 12. Between the door sheet 11 and the back-head 12 there are 5 also provided a number of stays 13 and outwardly and inwardly directed flanges 14 and 15 are provided on the door sheet 11 and the back-head 12, respectively, which are riveted together so as to form the door 10 opening. The back-head 12 has at either side near the top thereof a semi-circular extension 16 each of which is provided with a man-hole 17 having a door 18 held in place by a pair of yokes 19. This permits the 15 entry of workmen into the interior of the water space. The man-holes 17 communicate with a pair of longitudinal passageways 20, which are formed by semi-cylindrical connecting sheets 21 connected at 20 their upper edges with the U-shaped sections 1 and at their lower edges with the U-shaped sections 7. The connecting sheets 21 are connected at their rear ends with the semi-circular extensions 16 on the back-head 25 and at the front ends with the throat sheet 3. At each side of the fire-box a series of water-tubes 22 are provided having their ends swaged down and welded in holes passing through the connecting sheets 21. As 30 shown particularly in Fig. 6 the portions of the connecting sheets 21 in which the openings for the tubes are located, are strengthened by extending the ends of the U-shaped plates 7 along the underfaces of the connecting sheets 21 so as to cover and pass beyond the portions of the connecting sheets 21 provided with the openings to receive the water-tubes. It will be noted that the ends of the 35 U-shaped sections 7 are then riveted to the connecting sheets 21 beyond the positions of the openings provided for the water-tubes. While the water-tubes 22 are smaller in diameter at their ends, the water-tubes are of such a width and are so located as to be 40 closely adjacent to one another throughout their length. The construction is so arranged that the flue sheet 8 and throat sheet 3 act as a supporting column at the front of the fire-box and the door sheet 11 and 45 back-head 12 act as a column at the rear of the fire-box so that there is a rigid and permanent positioning of the parts by this means, the movements of which by differences in expansion and contraction or by 50 shocks from the fire-box supports on the frame will not affect any of the joints of the different portions of the fire-box. In order to preserve this arrangement and so as not to make the support of the various 55 parts depend upon the water-tubes, and so as furthermore to arrange the water-tubes to permit independent expansion and contraction thereof without loosening the joints between their ends and the parts of the fire- 60 box to which they are connected, the water-

tubes 22 are curved at their upper ends. This has the result of permitting a slight change in the curvature of the water-tubes whenever there is any difference in the expansion and the contraction of the water-tubes as compared with the columns previously referred to as supporting the front and rear of the fire-box. At the bottom of the fire-box there is a mud ring 23 which extends around the bottom of the fire-box and which is located at the rear of the fire-box 70 between the door sheet 11 and the back-head 12, and at the front of the fire-box between the throat sheet 3 and the flue sheet 8, suitable rivets being passed through the mud ring and the various sheets to which it is attached to hold the same in place. At the sides of the fire-box inverted U-shaped sections 24 are located over the mud ring, said U-shaped sections 24 having annular flanges 85 25 to which the lower ends of the tubes 22 are secured. The lower ends of the tubes 22 are swaged down to a smaller diameter so as to fit within the annular flanges. 90

As will be seen in Fig. 5 at the rear corners of the mud ring 23 the U-shaped sections 24 at the sides of the fire-box are welded to corner U-shaped sections 26, which in turn are welded to short end U-shaped sections 27 located immediately adjacent to 95 the back-head 12. Screw plugs 28 permit the entry of tools for clearing the circulation spaces formed by the inverted U-shaped sections 24. At the front of the fire-box in order to permit the main portions of the 100 tubes 22 to be straight notwithstanding the inclined position of the throat sheet 8, the sides of the mud ring 23 are extended forwardly a short distance beyond the lower end of the throat sheet 8 and the inverted U-shaped plates 24 are extended forwardly in a similar manner to cover the sides of the mud ring 23 up to their extreme ends. The inverted U-shaped plates 24 also have screw plugs 29 to permit the entry of tools 105 in the water spaces therein. At the top of the fire-box the back-head 12 has upon its inner face a reinforcing plate 30 made somewhat in the form of a figure 8, the openings in which register with the man-holes 17. 110 The reinforcing plate 30 has a pair of transverse ribs 31 to strengthen the back-head at this point and make the same as strong as if the man-holes 17 had not been formed in the back-head. Brackets 32 extending over 115 and bolted to the flanges 31 connect the flanges by means of longitudinal stays 33 with the throat sheet 3 and with the boiler sheet 3a. 120

When a fire-box is constructed as indicated above, the top and bottom portions of the water chamber are supported by the front pedestal formed by the flue sheet 8, and the throat sheet 3, and the rear pedestal formed by the door sheet 11, and the back- 125 130

head 12. Any expansions and contractions in these pedestal supports do not, however, necessarily affect the water-tubes 22 and their connections to the fire-box to the same degree, inasmuch as the tubes 22 are arched outwardly to a certain degree to permit the independent expansion and contraction of the water-tubes 22. It will thus be evident that the joints between the ends of the water-tubes and the fire-box will not become disconnected or loosened owing to any expansions or contractions or shocks which occur in the fire-box. Furthermore, there is no weakening of the connecting plates 21 owing to the passage of the water-tubes 22 into the same, owing to the fact that the ends of the U-shaped plates 7 are extended a considerable distance beyond the positions of the water-tubes 22, thus adequately strengthening the portion of the connecting plates 21 into which the water-tubes 22 pass. As previously pointed out the crown sheet and roof sheet are arched somewhat so as to conform somewhat to the position of the fire-tubes 9. They are, however, not arched sufficiently to provide a downward component that will in any way disturb or act as an undue stress upon the staying plates 4. It will be noted furthermore that the crown sheet and roof sheet are arranged in such a position as to be connected tangentially to the edges of the connecting sheets 21, inasmuch as the stresses upon these parts at the points of union are tangential to the semi-cylindrical connecting plates 21. The portion of the back-head 12 which is provided with the man-holes 17 is also adequately reinforced by the reinforcing plate 30, which reinforcing plate 30 is connected by the stays 33 with the throat sheet 3 and the boiler sheet 3a. It will of course be understood that the U-shaped sections 1 and 7 are arranged with upwardly directed flanges and curved contours so as to remove the rivet joints from the action of the flames in the fire-box and so as to permit longitudinal expansion and contraction without loosening the joints as in accordance with previous constructions provided with such sections.

When it is desired to inspect, clean or wash or to make any repairs to the interior of the water space, that is to say, to the flanges of the U-shaped plates 7, the staying means 4 attached thereto, the longitudinal connecting plates 21, the joints between the ends of the water tubes 22 and the connecting plates 21 or any of the other parts located upon the interior of the water space above the fire-box, it is merely necessary for a man to enter one of the man-holes 17 without the necessity of disconnecting any of the parts. The longitudinal passageways 20 on the two sides of the water space provide ample room for the making

of repairs in this manner. Furthermore, if it is desired to make any repairs to the lower ends of the water-tubes 22, this may be readily done by sawing out the portion of the inverted U-shaped plate attached to the mud-ring 23 located immediately below the particular tube and then re-inserting the tube with a portion of an inverted U-shaped plate fitting in the portion removed and welding this inserted portion to the remainder of the inverted U-shaped plate located at that point. The plugs 28 and 29 may be removed at any time to permit the cleaning of the water spaces formed by the U-shaped plates located over the stays of the mud-ring 23.

While I have described my invention above in detail, I wish it to be understood that many changes may be made therein without departing from the spirit of my invention.

I claim:

1. A fire-box comprising a door sheet, a flue sheet, a water chamber comprising a crown sheet, a roof sheet and lateral semi-cylindrical connecting sheets the water chamber being connected to the tops of the door sheet and flue sheet, and water-tubes connected to the water chamber and located at the sides of the fire-box.

2. A fire-box comprising a door sheet, a flue sheet, a water chamber comprising a crown sheet, a roof sheet and lateral semi-cylindrical connecting sheets the water chamber being connected to the tops of the door sheet and flue sheet and vertical water-tubes connected to the water chamber and located at the sides of the fire-box.

3. A fire-box comprising a door sheet, a flue sheet, a water chamber comprising a crown sheet, a roof sheet and lateral semi-cylindrical connecting sheets the water chamber being connected to the tops of the door sheet and flue sheet, water-tubes connected to the water chamber and located at the sides of the fire-box, and staying means between the crown and roof sheets allowing longitudinal passageways in the connecting sheets.

4. A fire-box comprising a door sheet, a flue sheet, a water chamber comprising a crown sheet, a roof sheet and lateral semi-cylindrical connecting sheets the water chamber being connected to the tops of the door sheet and flue sheet, vertical water-tubes connected to the water chamber and located at the sides of the fire-box, and staying means between the crown and roof sheets allowing longitudinal passageways in the connecting sheets.

5. A fire-box comprising a door sheet, a flue sheet, a water chamber comprising a crown sheet, a roof sheet and lateral semi-cylindrical connecting sheets the water chamber being connected to the tops of the

- door sheet and flue sheet, and water-tubes connected to the water chamber located at the sides of the fire-box, and a back-head having man-holes giving access to the spaces in the connecting sheets.
6. A fire-box comprising a door sheet, a flue sheet, a water chamber comprising a crown sheet, a roof sheet and lateral semi-cylindrical connecting sheets the water chamber being connected to the tops of the door sheet and flue sheet and vertical water-tubes connected to the water chamber located at the sides of the fire-box, and a back-head having man-holes giving access to the spaces in the connecting sheets.
7. A fire-box comprising a door sheet, a flue sheet, a water chamber comprising a crown sheet, a roof sheet and lateral semi-cylindrical connecting sheets the water chamber being connected to the tops of the door sheet and flue sheet, water-tubes connected to the water chamber and located at the sides of the fire-box, staying means between the crown and roof sheets allowing longitudinal passageways in the connecting sheets, and a back-head having man-holes giving access to the spaces in the connecting sheets.
8. A fire-box comprising a door sheet, a flue sheet, a water chamber comprising a crown sheet, a roof sheet and lateral semi-cylindrical connecting sheets, the water chamber being connected to the tops of the door sheet and flue sheet, vertical water-tubes connected to the water chamber and located at the sides of the fire-box, staying means between the crown and roof sheets allowing longitudinal passageways in the connecting sheets, and a back-head having man-holes giving access to the spaces in the connecting sheets.
9. A fire-box comprising a door sheet, a flue sheet, a water chamber comprising a crown sheet, a roof sheet and lateral semi-cylindrical connecting sheets the water chamber being connected to the tops of the door sheet and flue sheet, water-tubes connected to the water chamber and located at the sides of the fire-box, staying means between the crown and roof sheets allowing longitudinal passageways in the connecting sheets, and a T-shaped back-head having man-holes giving access to the spaces in the connecting sheets.
10. A fire-box comprising a door sheet, a flue sheet, a water chamber comprising a crown sheet, a roof sheet and lateral semi-cylindrical connecting sheets, the water chamber being connected to the tops of the door sheet and flue sheet, vertical water-tubes connected to the water chamber and located at the sides of the fire-box, staying means between the crown and roof sheets allowing longitudinal passageways in the connecting sheets, and a T-shaped back-head
- having man-holes giving access to the spaces in the connecting sheets.
11. A fire-box having a water chamber, comprising a crown sheet, a roof sheet and semi-cylindrical connecting sheets connecting the sides thereof, and water tubes connected to the water chamber and located at the sides thereof.
12. A fire-box having a water chamber, comprising a crown sheet, a roof sheet and semi-cylindrical connecting sheets connecting the sides thereof tangent to the crown and roof sheets, and water tubes connected to the water chamber and located at the sides thereof.
13. A fire-box comprising a sectional crown sheet, a sectional roof sheet, semi-cylindrical connecting sheets connecting the sides thereof and staying means connecting the sections of the crown and roof sheets but leaving open the spaces in the connecting sheets.
14. A fire-box comprising a sectional crown sheet, a sectional roof sheet, semi-cylindrical connecting sheets connecting the sides thereof tangent to the crown and roof sheets, and staying means connecting the sections of the crown and roof sheets but leaving open the spaces in the connecting sheets.
15. A fire-box comprising a door sheet, a flue sheet, a water chamber comprising a crown sheet, a roof sheet and lateral, semi-cylindrical connecting sheets, the water chamber being connected to the tops of the door sheet and flue sheet and curved water-tubes connected to the water chamber and located at the sides of the fire-box.
16. A fire-box comprising a door sheet, a flue sheet, a water chamber comprising a crown sheet, a roof sheet and lateral, semi-cylindrical connecting sheets, the water chamber being connected to the tops of the door sheet and flue sheet and water tubes having reduced ends connected to the water chamber and located at the sides of the fire-box.
17. A fire-box comprising a door sheet, a flue sheet, a water chamber connected to the tops of the door sheet and flue sheet, vertical water-tubes connected to the water chamber located at the sides of the fire-box, a mud ring, and an inverted U-shaped plate connecting the mud ring to the water-tubes.
18. A fire-box comprising a door sheet, a flue sheet, a water chamber comprising a crown sheet, a roof sheet and lateral connecting sheets the water chamber being connected to the tops of the door sheet and flue sheet, vertical water-tubes connected to the water chamber located at the sides of the fire-box, a mud ring, and an inverted U-shaped plate connecting the mud ring to the water-tubes.
19. A fire-box comprising a door sheet, a flue sheet, a water chamber comprising a

5 crown sheet, a roof sheet and lateral semi-cylindrical connecting sheets the water chamber being connected to the tops of the door sheet and flue sheet, water-tubes connected to the water chamber located at the sides of the fire-box, a back-head having man-holes giving access to the spaces in the connecting sheets, a mud ring, and an inverted U-shaped plate connecting the mud 10 ring to the water-tubes.

15 20. A fire-box comprising a door sheet, a flue sheet, a water chamber comprising a crown sheet, a roof sheet and lateral semi-cylindrical connecting sheets the water chamber being connected to the tops of the door sheet and flue sheet, vertical water-tubes connected to the water chamber located at the sides of the fire-box, a back-head having man-holes giving access to the 20 spaces in the connecting sheets, a mud ring, and an inverted U-shaped plate connecting the mud ring to the water-tubes.

25 21. A fire-box comprising a door sheet, a flue sheet, a water chamber comprising a crown sheet, a roof sheet and lateral semi-cylindrical connecting sheets the water chamber being connected to the tops of the door sheet and flue sheet, water-tubes connected to the water chamber and located at 30 the sides of the fire-box, staying means between the crown and roof sheets allowing longitudinal passageways in the connecting sheets, a back-head having man-holes giving access to the spaces in the connecting sheets, 35 a mud ring, and an inverted U-shaped plate connecting the mud ring to the water-tubes.

40 22. A fire-box comprising a door sheet, a flue sheet, a water chamber comprising a crown sheet, a roof sheet and lateral semi-cylindrical connecting sheets the water chamber being connected to the tops of the door sheet and flue sheet, vertical water-tubes connected to the water chamber and located at the sides of the fire-box, staying 45 means between the crown and roof sheets allowing longitudinal passageways in the connecting sheets, a back-head having man-holes giving access to the spaces in the connecting sheets, a mud ring and an inverted 50 U-shaped plate connecting the mud ring to the water-tubes.

55 23. A fire-box comprising a door sheet, a flue sheet, a water chamber comprising a crown sheet, a roof sheet and lateral connecting sheets the water chamber being connected to the tops of the door sheet and flue sheet, and water-tubes connected to the water chamber and located at the sides of the fire-box, the crown sheet and connecting sheets 60 overlapping to receive the ends of the water-tubes.

24. A fire-box comprising a door sheet, a flue sheet, a water chamber comprising a

crown sheet, a roof sheet and lateral connecting sheets the water chamber being connected to the tops of the door sheet and flue sheet and vertical water-tubes connected to the water chamber and located at the sides of the fire-box, the crown sheet and connecting sheets overlapping to receive the ends of 65 the water-tubes.

70 25. A fire-box comprising a door sheet, a flue sheet, a water chamber connected to the tops of the door sheet and flue sheet, water-tubes connected to the water chamber, located at the sides of the fire-box, a mud ring, and an inverted U-shaped plate connecting the mud ring to the water-tubes, the tubes having reduced ends connected to the inverted U-shaped plate.

75 26. A fire-box comprising a door sheet, a flue sheet, a water chamber connected to the tops of the door sheet and flue sheet, vertical water-tubes connected to the water chamber, located at the sides of the fire-box, a mud ring, and an inverted U-shaped plate connecting the mud ring to the water-tubes, the tubes having reduced ends connected to the inverted U-shaped plate.

80 27. A fire-box comprising a door sheet, a flue sheet, having an inclined lower end, a water chamber connected to the tops of the door sheet and flue sheet and vertical water-tubes connected to the water chamber at the sides of the fire-box, and extending forwardly beyond the lower end of the flue sheet.

85 28. A fire-box comprising a door sheet, a flue sheet, having an inclined lower end, a water chamber connected to the tops of the door sheet and flue sheet, vertical water-tubes connected to the water chamber at the sides of the fire-box and extending forwardly beyond the lower end of the flue sheet, a mud ring and an inverted U-shaped 90 plate connecting the mud ring to the tubes and extending forwardly beyond the lower end of the flue sheet.

95 29. A fire box comprising a crown sheet, a roof sheet, semi-cylindrical connecting sheets connecting the sides thereof and a boiler, one end of the space between the roof sheet, crown sheet and the connecting sheets being open and in communication with the boiler.

100 30. A fire box comprising a crown sheet, a roof sheet, semi-cylindrical connecting sheets connecting the sides thereof, a boiler shell, and a throat sheet connecting the fire box to the boiler shell.

105 110 In testimony that I claim the foregoing I have hereunto set my hand.

CHARLES DUCAS.
